UNITED STATES PATENT OFFICE.

JOHN N. SHYMANSKI, OF LOUISVILLE, KENTUCKY.

PROCESS OF TREATMENT OF CLAY CHALK.

No. 859,699.

Specification of Letters Patent.

Patented July 9, 1907.

Application filed January 15, 1907. Serial No. 352,400.

To all whom it may concern:

Be it known that I, JOHN N. SHYMANSKI, a citizen of the United States, and a resident of Louisville, in the county of Jefferson and State of Kentucky, have invented a new and Improved Process of Treatment of Clay Chalk, of which the following is a full, clear, and exact description.

This invention has reference to improvements in the process of treating the material commonly known as clay chalk, as used for marking purposes by tailors and others. This chalk is usually placed on the market for tailors' use in the form of thin, rectangular pieces tapering in cross section at both sides, providing opposite sharpened edges. These edges after slight use in marking, become dull or break and require frequent sharpening, owing to the soft, brittle and fragile character of the clay chalk. These qualities of the chalk also render it easily broken when dropped on the table, floor, etc. or in anywise roughly handled. I have discovered a treatment for this clay chalk, which, while not impairing its marking qualities, largely removes its fragile and soft character, rendering it tough and capable of taking a sharp marking edge and holding it much longer when in use for marking purposes, than the commercial article.

My improved treatment consists in taking the clay chalk, preferably in the form as now sold for marking purposes, and soaking it in machine oil. This soaking

should continue until the chalk has become thoroughly saturated, the time required for this operation depending upon the thickness of the pieces which the oil is to penetrate; for ordinary thicknesses a day's soaking will be found sufficient. After the soaking of the chalk in the oil is complete, it is removed and placed in a suitable position to dry. When the chalk is thoroughly dry, it is ready for use in the ordinary manner. It will be found that while its use as a marker is in no wise rendered inferior by the treatment, it has lost practically all of the features of disadvantage of the ordinary commercial marker.

Having thus described my invention I claim as new and desire to secure by Letters Patent:

- 1: The herein described process of treating clay chalk for marking and other purposes, which consists in soaking it in oil, and thereafter permitting the same to dry. 45
2. The herein described process of treatment of clay chalk for marking and other purposes, which consists in soaking it in machine oil, and thereafter permitting the same to dry.
3. The herein described process of treating chalk for marking and other purposes, which consists in soaking it in machine oil to the point of saturation, and thereafter removing the chalk and permitting it to dry.

In testimony whereof I have signed my name to this specification in the presence of two subscribing witnesses. 55

JOHN N. SHYMANSKI.
